(57) **CLAIM**

The ornamental design for a plug device, as shown and described.

DESCRIPTION

FIG. 1 is a perspective view of a plug device of the present invention, with a side member depicted in broken lines;

FIG. 2 is a front view thereof;

FIG. 3 is a rear view thereof;

FIG. 4 is a left side view thereof;

FIG. 5 is a bottom view thereof;

FIG. 6 is a top view thereof; and,

FIG. 7 is a section view thereof with reference to the cross-section arrows depicted in FIG. 6.

The broken lines in the drawings depict environmental subject matter only and form no part of the claimed design.

1 Claim, 6 Drawing Sheets
